UNITED STATES PATENT OFFICE.

SVEN HOLSTROM, OF HIGHLAND PARK, ILLINOIS.

GRAPPLER HOOK.

1,258,220.

Specification of Letters Patent.

Patented Mar. 5, 1918.

Application filed October 28, 1915. Serial No. 58,321.

To all whom it may concern:

Be it known that I, SVEN HOLSTROM, a citizen of the United States, residing at Highland Park, in the county of Lake and

5 State of Illinois, have invented certain new and useful Improvements in Grapple-Hooks, of which the following is a specification.

My invention relates to a hook and particularly to means to normally maintain the 10 sections thereof closed against accidental opening but permitting opening at desired times through suitable operation, in the respects mentioned therefore being especially desirable as a grapple hook structure.

15 Specifically, the invention aims to provide a hook having a plurality of pivoted parts connected by a link to which a chain or the like is attached, and which link has a curved or cammed portion and a substantially straight portion, both movable through 20 enlarged eyes in the hook members.

Also I particularly aim to provide means to reinforce the pivoted hook sections directly above the portions where they are 25 engaged by the said link, such reinforcing means particularly being in the nature of a flange to overlap the complementary section of the hook.

I also aim to provide an effective means 30 to prevent relative lateral movement of the pivoted sections, when closed.

With the above and additional objects such as will hereinafter appear, in view, the 35 invention has been embodied in one preferred form as illustrated in accompanying drawings, wherein:

Figure 1 is a front elevation of my improved hook structure;

Fig. 2 is a side elevation of my improved 40 hook structure;

Fig. 3 is a front elevation of my improved hook structure showing the hook sections in open position, and

Fig. 4 is an inverted plan view of the 45 pivoted hook sections.

Referring specifically to the drawings, the hook is shown as comprising two sections 1 and 2 pivoted together as by means of a pin 3 approximately midway of their ends. 50 Each section 1 and 2 is provided with an ordinary hook portion 4 to inclose a space 5 through which the element supported passes. As a safeguard against spreading of the portions 4 and in order to reinforce 55 such portions, one section 4 is bifurcated to provide a slot 6 and the other portion 4 is

reduced to form a tongue 7 which enters said slot 6 when the sections are closed as in Figs. 1, 2, and 4.

Each section 1 and 2 has a connecting 60 arm 8, having an aperture 9 enlarged with respect to the transverse sectional area of the link 10 which passes through said eyelets.

By means of this single link 10, I control 65 the positions of the two hook members 1 and 2. Therefore, this link should have one or more substantially straight portions 11 and one or more curved portions 12.

In use, say the parts in open position as in 70 Fig. 3, the load is connected to the hook within space 5 as the hook is lowered. Such action draws the link 10 to the vertical position shown in Fig. 1 and in moving to such position, one of the portions 12 engages the 75 arms 8 at the apertures 9, serving as a cam in connection with such arms and drawing the arms together to the position shown in Fig. 1 and holding said arms against accidental displacement. 80

If the hook sections are to be opened, the action is accomplished while the chain which supports the hook is slack and by turning the link 10 until one of the straight portions 12 is disposed within the apertures 9, 85 whereupon, due to the enlargement of the apertures, the hook sections may be swung relatively, with arms 8 moving on one straight portion 11, to open the hook portions as in Fig. 3, to permit detachment or 90 attachment of the load.

It will be realized that considerable strain will fall upon the arms 8 above the apertures 9 and to obviate this drawback, I provide an arcuate flange 13 to overlap and engage 95 the upper portions of arm 8 of section 1. Flange 13 is preferably formed integral with the arm 8 of section 2.

As previously intimated, the hook is supported from a chain or flexible element 100 which may connect in any suitable way directly to the link 10 or, if preferred, may connect with a link such as is shown at 14 in Fig. 1. It will be realized that the closing of the hook is automatic through tightening of the supporting chain therefor. 105

If sections 1 and 2 were permitted to open to their fullest extent, injurious binding of arms 8 at the apertures 9 with link 10 would result in breaking of the arms in some instances and for this reason, I prefer to provide an abutment 15 on one section, for in- 110

stance, section 2, to be engaged by the section 1, to limit the movement of the sections to the open position of Fig. 3.

Since merely the preferred embodiment 5 has been illustrated and described, it is to be understood that changes in the details of construction may be resorted to within the spirit and scope of the appended claim.

I claim:

10. In a suspending device, a plurality of relatively movable suspending sections, each section having a connecting arm provided with an aperture, one of said arms having a flange thereon, a link passing through said 15 aperture adapted to close and normally maintain the sections in a closed position,

said apertures being enlarged with respect to the portion of the link passing therethrough to permit the sections to open thereon, one of said arms being enlarged adjacent its aperture to permit the sections to open thereon, said link being provided with a cam portion, one of said sections being provided with an abutment formed integral therewith and engageable by the other section substantially as described. 20 25

In testimony whereof I affix my signature in the presence of two witnesses.

SVEN HOLSTROM.

Witnesses:

O. L. OLESEN,
ROBERT W. PEASE.
